FORMING AND ASSEMBLING MACHINE

Harold C. Coppins, Buffalo, N. Y., assignor to
 F. N. Burt Company, Limited, Toronto, Ontario, Canada, a corporation of Ontario, Canada

Application March 29, 1933, Serial No. 663,267

61 Claims. (Cl. 93—43)

This invention relates to improvements in a forming and assembling machine, and more especially with reference to details, it relates to improvements in a machine for assembling receptacle parts and for performing certain operations upon the assembled parts.

It is an object of the invention to provide an apparatus of this nature which will function in a substantially automatic manner and at high speeds so that when the apparatus is once set up a minimum of manual attention will be required and the units fabricated by said apparatus may be substantially free from defects, and be produced at low cost.

15 A further object is that of furnishing an apparatus comprising a plurality of units largely capable of individual employment, but which units preferably—according to the teachings of the present invention—are correlated to sequentially or simultaneously function in harmony with one another to achieve the results desired.

Moreover, while of necessity an apparatus of the present type is complicated, it will be found that such complication is but relative, and that 25 consistent with the achievement of the results desired, the machine includes few parts, each individually simple and rugged in construction, and which when assembled, cooperate over long periods of time with freedom from any difficulties.

30 Other objects of the invention will be in part pointed out in the following detailed disclosure and will be in part obvious in connection therewith.

35 The invention accordingly comprises the several steps and the relation and order of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

40 For a more complete understanding of the nature and objects of the invention, reference is made to the following detailed description of an illustrative but preferred embodiment of the invention, and to the accompanying drawings, in which:—

50 Figure 1 is a side view of the machine;

Figure 2 is an end view thereof;

Figure 3 is a plan view of such machine;

Figure 4 is a view similar to Figure 3, showing certain of the mechanisms removed to disclose 55 underlying constructions;

Figures 5, 6, 7, 8, 9, 10, and 11 are transverse sectional views of the control shaft and showing the several controlling cams associated therewith, together with the followers which cooperate with these cams;

5 Figure 12 is a sectional side view of the fluid control valve;

Figures 13 and 14 are transverse sectional views taken along the lines 13—13 and 14—14 respectively, and in the direction of the arrows 10 as shown in Figure 12;

Figure 15 is a perspective view of the parts of the receptacle as they are initially positioned within the machine;

Figure 16 is a similar view after the hinge 15 member has been brought to a position adjacent the receptacle parts;

Figure 17 is another perspective view showing the hinge member applied to the receptacle;

Figure 18 is a similar view showing the receptacle ready to receive the tray;

Figure 19 illustrates the receptacle after it has passed through the machine;

Figure 20 is a partly sectional side view of the mechanism which is disposed adjacent the initial 25 station of the machine;

Figure 21 is a fragmentary end view on reduced scale of certain of the mechanism which is disposed beyond the mechanism specifically shown in Figure 20;

Figure 22 is a partly sectional end view of certain of the stop mechanism as occurring at the initial station of the machine;

Figure 23 is a transverse sectional view taken along the lines 23—23 and in the direction of 35 the arrows as indicated in Figure 22;

Figure 24 is a view similar to Figure 22 but showing further mechanism which permits the feeding of and serves to properly dispose receptacle portions one with reference to the other; 40

Figure 25 is a partly fragmentary side view of certain of the mechanism employed to align the box portions;

Figure 26 shows an operating and driving part which is associated with the mechanism illustrated in Figure 25;

Figure 27 is a plan view of the mechanism shown in Figure 25;

Figure 28 is a side elevation of the mechanism generally disposed adjacent the next station of 50 the machine and which serves to feed the hinge member to the box portions;

Figure 29 is a detailed view of the magazine which preferably forms a part of the mechanism at this station;

Figure 35 is an end view of the mechanism as shown in Figure 33;

Figure 36 is an elevation illustrating the apparatus disposed adjacent the next station of the machine, and by means of which those functions are achieved which are preliminary to the application of the tray;

Figure 37 is a partly sectional side view of certain of the apparatus occurring at the machine station described in connection with Figure 36;

Figure 38 is a side elevation of certain of the parts as shown in Figure 36;

Figure 39 is a front elevation partly in section showing the apparatus which occurs at the machine station where the tray or collar is applied to the receptacle base;

Figure 40 is a sectional view of certain of the parts as shown in Figure 39;

Figure 41 is a partly sectional side view of the mechanism preferably employed to control the collar or tray discharging mechanism;

Figure 42 is a transverse sectional view of the valve which forms a part of such mechanism;

Figures 43, 44, and 45 are sectional views taken along the lines 43—43; 44—44 and 45—45, and in the direction of the arrows as indicated in Figure 42;

Figure 46 is a bottom plan view of the tray mounting head, which is controlled by the apparatus described in the preceding five views and which has heretofore been best illustrated in Figures 39 and 40;

Figure 47 is a front elevation of the mechanism by means of which the parts of the receptacle are brought to occupy proper and final relative positions;

Figure 48 is a partly sectional side view similar to Figure 47;

Figure 49 is a front elevation of the mechanism which serves to discharge the completed receptacle;

Figure 50 is a plan view of the mechanism as shown in Figure 49, and

Figure 51 shows the operating mechanism employed in conjunction with the apparatus disposed adjacent the station described in Figures 49 and 50.

In these several views a preferred embodiment of the invention has been illustrated and, as hereinafter will appear, this embodiment functions in a cycle of operation according to which:

First.—Receptacle portions are suitably fed to the machine, either from a preceding apparatus or otherwise, and these portions are received and retained in proper association with each other and with the operative mechanisms;

Second.—The receptacle portions are aligned with respect to each other both horizontally and vertically;

Third.—A hinge strip or member is fed towards the receptacle portions, and, if desired, is treated as by adhesive application so that it will remain in association with such portions;

Fourth.—The hinge strip or member is brought into contact with the receptacle portions and applied thereto so that the portions are connected to each other;

Fifth.—Glue is applied to the surfaces of one

receptacle portion, or else, if that portion has been previously treated, the adhesive or other material is brought to an operative condition;

Sixth.—A collar or tray is placed within the treated receptacle portion and properly disposed with reference to the hinge strip or member to insure that the latter may not be accidentally displaced;

Seventh.—The receptacle portions are manipulated so that all parts applied thereto are firmly pressed into contact with adjacent parts to assure against accidental detachment or relative movement, and

Eighth.—The completed receptacle is discharged.

As will be apparent the teachings of the invention might be employed advantageously to perform any of the preceding operations, or, if desired, to perform additional operations. Certain steps might be omitted or added, and additionally, while a receptacle of a particular type has been illustrated, and while this receptacle is preferably of paper or cardboard material, it will be patent that the machine parts might readily be modified within the scope of this invention so that receptacles of different configuration and material might be handled, or, in fact so that units merely having characteristics similar to receptacles might be advantageously operated upon by the machine.

Referring particularly to Figs. 1 to 4, inclusive, a deck 60 is spaced above a second deck 61, by means of supporting side walls 62. Both decks may be mounted by legs 63 provided with a base portion. A turntable 66 is mounted above deck 60 and flange portion 65 may extend respectively from the upper face of the deck and the lower face of the turntable so as to provide a confined space for the housing of gears 67 and 68. These gears have a ratio of two to one, and the gear 67 is attached to the under face of the turntable or else to the shaft mounting the same; it being obvious that as the gear 68 makes two revolutions, the gear 67 and the turntable connected therewith will complete one rotation.

As shown especially in Fig. 4, a motor 69 may be secured to the underside of the deck 60, and serves by means of any suitable drive 70, to rotate the clutch part 71. Clutch part 72 may cooperate with the part 71 and is secured to a shaft 73 so that when the clutch is coupled, a gear 74 associated with such shaft will be rotated. The teeth of this gear mesh with the teeth of gear 75, by means of which shaft 76 is rotated. This shaft carries a sprocket gear 77 which, by means of a sprocket chain 78, serves to drive a similar gear 79 affixed to shaft 80. A shaft 83 is driven through bevel gears 82 by shaft 76. Moreover the shaft 76 serves, by means of a bevel gear 84 to rotate a similar gear 85, to which is affixed an element 86 of a Geneva stop movement, the second element 87 thereof being secured to shaft 88, which serves to drive the gear 68.

The clutch part 72 may be disengaged from the clutch part 71 by a throw-yoke 89 coupled to 65 rocking lever assembly 90, one part of which is link connected as at 91 to a series of operating handles 92, and another part of which is connected to a rod 93 coupled to an automatic operating mechanism contained within a casing 94. Receptacle portions or box units are produced by this improved apparatus, comprising, as shown in Fig. 15, a unit 95, which is to form the lid of the receptacle and unit 96 which is to become the base of the same. Both of these units are preferably— 75

although not necessarily—of identical dimensions and have, in the embodiment illustrated, upstanding flange portions 97. Preferably these units are imprinted before the present apparatus 5 cooperates with it, and regardless of whether they are formed or brought to the finished condition shown in Fig. 15 by providing an auxiliary apparatus, or whether such apparatus is entirely independent of the present machine, they are deposited upon a conveyor 98 with one box unit immediately following the preceding unit. The conveyor 98 (see Figs. 1, 20, and 22) may be driven by passing around a drum or pulley 99 mounted upon a shaft 100. Secured to this shaft is a 10 sprocket gear 101, the teeth of which are engaged by a sprocket chain 102. This chain, as shown in Fig. 4, engages a sprocket wheel 103 affixed to the shaft 80, and as a consequence, when the motor 69 operates and the clutch parts 15 are engaged, the conveyor will be moved.

As shown in Fig. 22, the conveyor feeds the units until the forward unit of a pair comes in contact with a step 104, at which time the conveyor commences to slide with reference to the 20 under faces of the receptacle units. The position occupied by the box parts at this point is known as station No. 1 of the machine. At this station mechanism is provided for transferring the units from the conveyor to the turn table 66. This 25 mechanism includes, as particularly shown in Figs. 20 to 23, a pair of guiding bars 105, upon which a carriage 106 is slidably mounted. These bars extend across the conveyor and overlie the turntable. The carriage is reciprocated along 30 the bars by a link 107, which has one of its ends connected to the carriage, its opposite end being connected to a lever 108 swingingly mounted, as at 109, and actuated by rod 110. This rod, as shown especially in Fig. 20, has its lower end coupled to a crank 111 affixed to shaft 112. This 35 shaft, by means of a gear 113, is driven by shaft 83, carrying a gear 114, the teeth of which mesh with gear 113 to effect this result.

The carriage 106 has shafts 115 which terminate in cam edge portions 115' and rotatably mount arms 116 having similar engaging cam portions. By virtue of springs 117, these cam portions cooperate so that the arms 116 normally extend downwardly. These arms mount at their 40 lower ends, by means of pivots 117', forks 118 which are adapted to engage with the box edges. It will be noted that springs 119 are associated with the pivot members 117' so that while the forks 118 may swing against the tension of the 45 springs and thus override receptacle portions, they are rigid with the arms 116 as the latter move forwardly. Also, while the arms 116 normally occupy the positions shown, they are capable of being swung with reference to shafts 115, in which case they will move outwardly along the shafts 50 against the compression of the springs 117. If such movement occurs, it will be apparent that pairs of contacts 120 associated with the shafts 115 and arms 116 will 55 swing and the circuit will be closed through the electromagnetic operating device 94 shown in Fig. 4 thus disengaging the main driving clutch 71, 72. As a result, neither the machine nor receptacle portions will be injured. 60 Further considering the mechanism at this point, it will be noted that the innermost shaft 115—i. e., the one which extends towards the direction from which the conveyor is moving—rigidly carries an arm 122 supporting a bar 123. As a result, it will 65 be obvious that when the carriage 106 is projected

to shift receptacle portions towards the turntable succeeding receptacle portions may not move into position. Such movement is allowed them only after carriage 106 has returned to substantially the position shown in Fig. 20.

It is proposed to shift receptacle portions or units in pairs. As shown in Fig. 3, the turntable 66 has guide strips 123 which are adjustably mounted upon its face and are arranged in pairs at right angles to each other, there being in the embodiment illustrated, eight such pairs. These strips define the end and one side zone, beyond which the receptacle portions may not be moved, and the second side zone is defined by an arm 126 adjustably coupled, as at 127, to one arm 15 of a bell crank lever 128. The bellcrank lever tends to constantly shift the arm 126 to press against the outer side edge of the receptacle unit, by virtue of a spring 129. The bell-crank lever may, however, be shifted so that this will not 20 occur by extending such lever in the form of an arm 130 carrying a roller 131 for cooperation with the edge of a cam disk 132 disposed centrally of the turntable. This disk is guided and retained against displacement by bolts 133 which extend 25 through slots 134 in its body. The disk, while relatively immovable with reference to the deck of the machine, is capable of a slight shifting action and a spring 135 tends normally to maintain it in a predetermined position, as shown in 30 Fig. 3, it being obvious that one end of the spring is connected to the cam disk and the opposite end to one of the bolts 133. A shifting of the cam disk to the position shown in Fig. 3 is effected by a pivoted lever 136 upon the centrally fixed 35 portion of the machine, which is encircled by the cam disk 132. One end of this lever cooperates with a cam 137 while the opposite end of the same engages a pin 138 secured to the cam disk or ring. Consequently when the cam 137 40 engages the lever 136, the cam disk will be shifted against the action of the spring 135 and the rollers 131 will cause the bell-crank levers 128 to be rocked so as to shift the arms 126, or else the latter will be permitted to continue in contact 45 with the side edge of the receptacle portion, this being contingent upon the position occupied by the rollers with reference to the edge of the ring or disk 132.

At the time that the receptacle portions are 50 being moved by the carriage 106 into the space defined by the strips 123 and 125 and the arm 126, the latter will be swung so as to provide ample space to permit this result. To this end the parts are so timed that projection of the 55 carriage 106 occurs just prior to the time that the cam 137 rocks the arm 136. Consequently the roller 131, which is adjacent station No. 1 of the turntable will be in contact with the extended or dwell portion of the cam ring, thus 60 assuring the result desired. Immediately thereafter the arm 126, under the influence of spring 129, will swing to box retaining position, the cam 132 having been shifted to permit this result.

With a view to additionally retaining the box 65 parts against movement, a presser foot may be employed. As shown in Figs. 20, 24 and 27, this may take the form of a strip or plate 139 disposed to one side of the center of the frame, as defined by the strips 123 and 125 and the arm 70 126. One presser foot is associated with each of the frames and actuation of this member may be conveniently obtained, as for example, by mounting the same upon a lever 140 secured to a bracket 141 attached to the turntable. The inner 75

end of this lever cooperates with a bar or rail 142 so that if such inner end is depressed by the rail, the presser foot or strip 139 will be elevated, a spring 143 being employed to constantly induce plate 139 to assume a depressed position. The rail 142 is mounted by bars 144 which are adjustably connected to a rockingly mounted lever 145, which lever tends to assume a depressed position under the influence of a spring 146. Elevation of the inner end of the lever 145 may be secured by means of a cam 147 attached to shaft 80 cooperating with a follower 148 carried by rockingly mounted lever 149, the inner end of which is connected to a rod 150 extending in line with the turntable axis and carrying a contact member 151 engaging the inner end of lever 145 to elevate the same and consequently depress the outer lever end and the rail 142 to correspondingly elevate the strip or plate 139.

20 This plate 139 is in elevated position at the discharge station of the machine and also at the first station heretofore described, as shown in Fig. 3. Consequently the receptacle portions may be freely associated with the turntable frame, but
25 subsequent to such association, and incident first, to the timing of the cam 147, and second due to the fact that the rail 142 extends only adjacent stations Nos. 1 and 8 of the machine, the presser foot will engage the box or receptacle portions. In such engagement it is preferred,
30 for reasons which will be apparent hereinafter, that direct pressure be exerted only against the cover portion or unit 95 of the receptacle.

After the foregoing operation of the parts, the turntable shifts under the action of gears 67—68, so that the frame, with the box units retained therein, occupies station No. 2 where the receptacle parts are aligned both horizontally and vertically. With this in mind, the mechanism shown in Figs. 25, 26, and 27 may be employed. Bars 152 are employed connected respectively to the end of a cross member 153 and a bolt 154. The latter rides within a slot 155 so that the bar associated with it may be adjusted transversely of the frame. It will, moreover, be noted that the parts are so positioned that the non-adjustable bar lies in line with the two adjacent and contacting side edges of the box units disposed within the frame, while the adjustable bar overlies the body or base unit of such receptacle portions. The cross member 153 is adjustably connected to a lever 156 which is mounted by a standard 157 and extends beyond the same. At its outer end it is connected to springs 158 and 159, the latter serving to normally maintain this end elevated and the former being capable of being tensioned to overcome the tendency of spring 159 and consequently to elevate the bars 152. Also, rockingly mounted by the standard 157 is an arm 160 which is link connected as at 161 to the lever 156. It will be noted that the body of the link is angularly disposed and consequently, as the outer end of lever 156 rocks downwardly, the arm 160 will shift inwardly, or to the right in Fig. 25. The lower end of arm 160 is link connected as at 162 to a slidably mounted bar 163 and a spring 164 connected to the bar and to the standard 157 serves normally to project the bar and shift the parts to a corresponding position. The bar 163 carries, adjacent its inner end, a presser foot 165, which is shiftable outwardly to a position beyond which the inner edges of the box units are not to extend. The spring 158 may be conveniently connected to a cam 166, which latter is connected to shaft 167 and, as shown especially

in Fig. 4, is connected by gears 168 to shaft 83. Consequently, with the parts properly timed, the frame carrying a pair of box units shifts to station No. 2 and thereupon the bars 152 descend to assure that the base unit moves into the same horizontal plane as that occupied by the lid unit. It will be recalled that the latter unit is mounted in a proper horizontal plane and in contact with the upper face of the turntable by continued action of the presser foot as provided by the strip or plate 139. Simultaneous with such horizontal aligning, the presser foot 165, which may be adjustably connected as at 169 to the bar 163, is projected to engage the outer edges of both box units to vertically align them and bring their inner edges into firm contact with the strip 125. 5 10 15

It will, of course, also be understood that, shown in Fig. 25, one or both bars 152 might, by means of springs 170, be cushioned so that there will be no possibility of the box parts being crushed as the inner end of lever 156 is lowered. With the receptacle units vertically and horizontally aligned, it is practicable to properly dispose a hinge strip or member with respect thereto. This operation occurs at station No. 3 of the machine and the turntable now shifts so that the aligned box units are brought into proper position within this station. The mechanism existing at this station is best shown in Figs. 28 to 32, inclusive. A carriage 171 is reciprocable along the bars 172 overlying the turntable adjacent station No. 3 and extending outwardly therefrom to a position well beyond the turntable edge. In order that the carriage may be reciprocated, any desirable mechanism may be employed. For example, a lever 173 may have its lower end rockingly supported, as at 174, by the base of the machine and be link-connected as at 175 to the carriage. This lever may be coupled by a rod 176 to a crank 177, as shown in Fig. 4. The crank is connected to a mutilated gear 178 meshing with the teeth of the gear 179 carried by shaft 76, and consequently, as the latter rotates, the lever 173 will reciprocate the carriage 171 along the bars 172 and provide for a period of rest as the carriage reaches positions adjacent the limits of its travel. The carriage supports suction heads 180 and 181 through the intermediary of a bar 182 mounting such heads adjacent its opposite ends, and which bar is in turn attached to rods 183 slidably supported in guideways 184 forming parts of the carriage 171. Springs 185 tend normally to maintain the bar and heads associated therewith in elevated condition, but the amount of such elevation, and the depression of such heads are controlled by a bar 186, which overlies the carriage 171, and has its lower edge in contact with rollers 187 secured to the upper ends of the rods 183.

In line with the outermost position of the head 181 is a magazine containing hinge strips or members 188. This magazine preferably includes a base 189 which is fed upwardly by means of a screw-threaded rod 190 encircled by a nut 191, and which nut is intermittently rotated by a pawl and ratchet mechanism 192. The pawl and ratchet mechanism may be actuated by a rod 193, which, as shown in Fig. 4, has a follower 194 cooperating with a cam 195 secured to shaft 80. Consequently, as such shaft rotates, the base of the magazine will be elevated, carrying with it the pile of strips or hinge members. These members are maintained against displacement one with respect to the other, by means of guide fingers 196. These guide fingers are preferably bored and terminate in nozzles 197 disposed ad-

5 jacent the upper end of the pile of strips or hinge members within the magazine. The nozzles are connected to a suitable source of compressed air (not shown), and it will thus be obvious that a force is constantly exerted which tends to maintain the uppermost strips in what might be termed a floating condition, and as such, capable of ready separation. The bar 186 is mounted by bellcranks 198, which latter may be link-connected as at 199. One of these bellcranks is continued in the form of a lever 200 connected by a rod 201, to a lever 202. A spring 203 cooperates with the latter lever to normally urge the rod 201 upwardly, and the bar 186 downwardly. This 10 movement of the parts is also induced by means of a spring 204, which has one of its ends conveniently anchored and its opposite end coupled to one of the bellcrank levers 198. The lever 202 carries a follower 205 cooperating, as shown in 15 Fig. 4, with a cam 206 mounted by shaft 80. Consequently, with the machine in operation, the bar 186 will be periodically depressed to correspondingly depress the bar 182 and the heads 181 carried thereby. In the intervals between 20 such depressing actions, the carriage 171 is reciprocated along the bars to transport hinge strips or members, as will hereinafter appear.

25 Tubes 207 and 208 are connected respectively to suitable sources of suction and pressure (not shown). As illustrated in Fig. 30, they are connected to double ports 209 and 210 of a plate 211. This plate is fixedly mounted upon carriage 171 and a plate 212 is also fixedly mounted by such carriage and in spaced relationship to the 30 plate 211. The plate 212 has double ports 213 and 214 corresponding to ports 209-210, and which ports are connected to tubes 215 and 216. The tube 215 is coupled to the heads 180 and 181 and the tube 216 is connected to a perforated base 35 217 mounted adjacent the limit of travel of the head 181. Interposed between the plates 211 and 212, and rockable with respect to the same is a plate 218, which has outstanding portions 219. The bar 186 carries a valve operating member 40 220 which—as the bar is depressed—may engage one of the operating portions 219.

45 The plate 218 is pivotally mounted between the plates 211 and 212, as for example, by means of a bolt 221. This plate, moreover, has ports 222^a and 223^a respectively, as well as a port 226^a. Accordingly, with the parts in the position shown in Fig. 29, it will be obvious that the tube 207 connects through ports 209 and 226^a with the lowermost of ports 213, so that the perforated base 50 217 is connected to the source of suction. The tube 208, through ports 210 and 225^a, and the uppermost ports 214, is connected with the tube 215, as a consequence of which air is being expelled from the heads 180. Now, as the bar 186 descends, the valve actuator 220 will engage the lefthand projection 219 to rock plate 218. Consequently, tube 207 will be connected through its righthand port 209 and port 226^a with port 214 55 connected to tubes 215. Thus, the heads 180 and 181 will become suction heads. Simultaneously, the lefthand port 210 of tube 208 will connect with tube 216 through port 222^a and the uppermost port 213 of the plate 212. Consequently, the perforated base 217 will thereupon be connected 60 with the source of pressure. Simultaneously with this connection, the heads 180 and 181 will lower, and as a result, the uppermost strip or hinge member 188 within the magazine will move into firm engagement with the underside of head 181, while 65 any strip upon the perforated base 217 will simi-

larly engage head 180. The carriage 171 will now shift, it being of course understood that prior to such shifting the bar 186 has been elevated to permit of a corresponding movement of the heads. Upon the carriage 171 reaching a position where the head 181 overlies the base 217, the bar 186 will again descend, which will cause the plate 218 to again rock to the left from the position shown in Fig. 29, under which circumstances the strip in association with head 181 10 will be deposited upon the base 217 and the strip applied to head 180 will be deposited to bridge the zone of contact between the pair of box units. 15

It is preferred that the strip be treated in its movement from the base 217 to the position at 20 which it is applied to the box units. If the strip or hinge member has been previously uncoated, such treatment should take the form of applying a layer of adhesive to the element. As shown in Fig. 28, this may be conveniently achieved by 25 employing a more or less conventional form of glue roller mounted upon a shaft 218, which is driven by a gear 219, meshing with the gear 220' rotated by a sprocket drive 221'. The glue roller may receive the adhesive from a pot 222', and 30 this entire unit may—if desired—be elevated so that the upper surface of the glue roller may engage the under face of the strip as it travels toward the box units. Such action may be conveniently achieved by mounting the shaft 218 35 and associated parts to move upwardly within a guideway 223, and by having the lower portion of the glue unit capable of elevation by means of a bellcrank lever 224, which has one of its arms in engagement with the unit, its opposite arm 40 being link connected as at 225 to a follower 226. This follower, as shown in Fig. 4, cooperates with a cam 227 mounted upon shaft 80 in order to achieve the desired results. The cam is so shaped and the shaft rotates at such speed that an elevation of the glue roller unit follows each time the carriage 171 moves towards the turntable. However, during the return stroke of this carriage, the glue roller unit is in lowered position. Thus, the under surface of the strip or member 45 will be coated and as the latter comes to a position overlying the adjacent surfaces of the box unit, the head 180 will be lowered to press the coated under face of the strip into contact with the upper adjacent side edges of the unit and at 50 this moment air under pressure will flow through the perforations of the head, assuring a complete separation of the strip therefrom and applying the same in contact with the box parts. The hinge strip 188 will thus be placed in adhering 55 engagement with the adjacent flanges of the box parts 95 and 96.

55 The turntable now shifts so that the box parts with the strip or member applied thereto, are transferred from station No. 3 to station No. 4, 60 at which point the strip or member is applied to the box in such manner that displacement thereof is precluded.

65 The mechanism at station No. 4 as best illustrated in Figs. 33 to 35, includes a cylinder 228 having ports 229, 230, 231, and 232. These ports are connected to a mechanism hereinafter described, and movable within the cylinder is a piston 233 connected to a rod 234. This mechanism overlies the turntable 66 and is supported upon 70 a frame 235. Secured to the lower end of the piston rod 234 is a plate or cross head 236, which mounts bolts 237 having slidable contact with the frame 235. The plate 236 has extensions 238 supporting links 239. These links are connected 75

to a bellcrank assemblage 240, the inner arms of which lie adjacent each other and mount clamping jaws 241. The members 240 of the assemblage are pivotally connected by interposed plates 242 integral with or affixed to a bar 243 mounted upon the bolts 237. Springs 244 are interposed between the plate 236 and the bar 243, these springs serving to yieldingly urge the bar 243 downwardly. The plates 242 additionally carry a bearing strip 245, which lies normally between the jaws 241. Thus, with the parts in the position shown in Fig. 33, if fluid under pressure is introduced through port 232, the rod 234 will move outwardly and downwardly against the action of a spring 246, which normally maintains it in elevated condition. This downward movement will continue until the bearing strip 245 engages the hinge member 188 and thus clamps the latter in position. The plates 242 will now cease downward movement, but the cross head 236 will continue its downward movement, thereby compressing springs 244 and through the links 239 swinging the jaws 241 to a position at which they wipe those portions of the strip which extend beyond the box portions into contact with the inner side faces of the adjacent flanges. Thereupon the jaws 241 close to an extent such that pressure is exerted against the faces of the strip pressing it firmly into adhering contact with the side faces of the box flanges and binding the box parts 95 and 96 together.

From the foregoing, referring particularly to Figures 3, 15 to 18, 25 and 27, it will be observed that the box or receptacle parts 95, 96 are entirely separate and independent of each other during the aligning of these elements with each other on the supporting table 66 and before the application of the hinge element 188. The two box elements are aligned with each other both vertically and horizontally prior to bringing the hinge element in position so as to hinge the two box parts together. Also it will be noted that the hinge strip or element 188 is entirely separate and independent of the box parts prior to placing the hinge strip into position to hinge the box parts together. As described, it will be clear that the hinge strip is not applied to secure the box parts together in hinged relation until after said box parts have been brought into alignment with each other by means of the mechanism described.

The turntable now shifts from station No. 4 to station No. 5, at which the base portion of the receptacle is treated to receive a tray or lining. The mechanism for performing this result, as best shown in Figs. 36, 37 and 38, includes rails 247 which overlie the turntable 66 and extend beyond the same. They may be conveniently supported by a standard 248 and slidably mount a carriage 249 supporting a cylinder 250. The carriage is reciprocated along the rails by a pitman or link 251 operated in a manner herein-after brought out. Underlying the rails or bars 247 is a glue tank 252 with which heaters 253 may be associated for the purpose of maintaining the adhesive in fluid condition. As is especially shown in Figs. 36 and 38, this tank contains an adhesive applying structure or applicator which may include grooved side walls 254 and a base 255. This structure is slidably supported for vertical movement by vertically disposed rails 256 positioned within the tank, and such movement is preferably effected by a pin and slot connection 257 with a rockingly mounted lever 258, the latter being engaged by a link

259 cooperating with a crank 260 secured to shaft 80. Thus, as the shaft revolves, the lever will be rocked to periodically elevate the glue applying structure. Overlying the adhesive applicator is the carriage 249, and the cylinder 250 corresponds in entire structure to the cylinder heretofore shown and described in connection with Figs. 33 and 34. The piston rod 261 (Fig. 37) extending from the cylinder 250 carries a support 262 mounting screw threaded rods 263. Adjustably carried by these rods are collars 264, which are link connected as at 265 to levers 266. The lower ends of these levers terminate in contact portions 267 and they are rockingly mounted by pivots 268, which latter are affixed in position within the slots of guides 269. Supported between and fixed with respect to the guides is a contact head 270, the under face of which is preferably ribbed as at 271, and this head, together with the guides 269, is carried by bolts 272, vertically shiftable with respect to the support 262. Thus, when the rod 261 is projected downwardly, all of the structure just described will be lowered. However, if the head 270 is supported against further downward movement, it will be obvious that the rods 263 will continue to lower, as a consequence of which the levers 266 may be rocked to have their contact portions 267 move outwardly with respect to the head 270. Thus, if the carriage and cylinder overlie the tank 252, and the glue applying structure within the latter is elevated, simultaneously with the admission of air to cylinder 250 it will be obvious that head 270 will contact with base 255 and that the contact portions 267 will engage the adhesively coated surfaces of parts 254. If the further flow of air is interrupted and the piston rod is now elevated, the parts 267 will primarily swing out of contact with the surfaces of parts 254 and thereupon the ribbed surface 271 of head 270 will move out of contact with base 255 and thereupon the entire carriage 249 may be shifted inwardly by means of the link 251 to a position at which it will overlie the frame receptacle portions adjacent station 5 of the machine.

The link 251, as shown in Fig. 3, is connected to a crank 272 secured to shaft 273. This shaft, as shown in Fig. 4, mounts a pinion 274, the teeth of which mesh with the teeth of a rack reciprocable by a link 276 secured to a crank 277. This crank is rocked by a link 278 connected to a crank 279, in turn connected to a mutilated gear 280 driven by a gear 281. The latter is mounted upon shaft 83 and consequently when this shaft rotates the carriage 242 will be reciprocated.

Referring now to Fig. 37, it will be obvious that when the carriage 249 reaches the position at which it overlies the base 96 of the box, it will be lowered when air is admitted in cylinder 250. Such lowering will cause the ribbed surface 271 to contact with the upper face of the box unit and will subsequently cause the portions 267 to similarly engage the side walls of such unit. As a consequence, these surfaces of unit 96 will be coated with adhesive in the manner indicated in Fig. 18 and thereupon by admitting air below the piston within the cylinder 250 the piston rod 261 will be elevated so that the turntable may shift to the next station. Simultaneously the carriage 249 will be moved along the rods or tracks 247 by means of the link 251, and will again contact with the surfaces of the adhesive applicator. The turntable now moves to

the sixth station of the machine, and adjacent such station the deck 60 mounts a conveyor 282, as shown in Fig. 39. This conveyor may be of conventional type and be driven by a drum or pulley 283 mounted upon shaft 284 carrying a bevel gear 285 meshing with a gear 286, coupled to gear 287, meshing with a further gear (not shown), which is in turn connected to a shaft 288, as shown in Fig. 20. This shaft carries a gear 289, meshing with the gear 290, in turn coupled to a gear 291 engaging with a gear 292. The latter gear is fixed to shaft 100 so that the same drive 102 which actuates conveyor 98 also actuates conveyor 282. The side edges of the latter conveyor are preferably defined by confining strips 293 spaced a sufficient distance to enable a tray or collar portion 294 to be accommodated thereon. As shown in Fig. 1, a stop 295 may be associated with the machine adjacent the end of travel of the conveyor 282 to thus prevent an over-feeding of the collar or tray portions.

At that point the apparatus is provided with rails 296 which overlie the conveyor and also 25 the turntable 66 of the machine. A carriage 297 is slidably supported upon these rails or bars and the latter may be mounted by a standard 298. Movement of the carriage along the rails is assured by the use of link 299, which, as shown in 30 Fig. 3, may be connected to a crank 300 rigid with crank 272 and shaft 273. Thus, this shaft provides a drive for the carriages, at both stations 5 and 6. Supported upon the carriage 297 is a cylinder 301 which, as shown in Fig. 40, 35 preferably has a piston 302 within its body and is provided with intakes 303 and 304 at its opposite ends, and is also formed with exhaust ducts 305. The piston mounts a connecting rod 306 which at its lower end supports a head 307. As 40 illustrated, especially in Figs. 40 and 46, this head mounts a plate 308 and may also have extending portions 309, one of which is formed with a suction opening 310. With a view to eliminating movement of the head, bolts 311 are 45 fixedly secured to the same and are slidably supported by the carriage 297. Movement of the plate 308 beyond the head is caused by mounting the same upon a piston rod 312, having at its upper end a piston 313, and which rod is normally urged upwardly by a spring 314. The lower end of the rod 306 is formed with a chamber 315 50 providing a cylinder for the piston 313, and the rod 306 is bored as at 316 and connected with a valve mounted at its upper end. This valve is best shown by Figs. 42 to 45, in conjunction with 55 Fig. 40. These views will disclose that the unit preferably includes a plate 317 mounted upon a shaft 318 and pressed by a spring 319 towards a plate 320. The latter plate is in turn overlaid by a rotatable plate 321, beyond which a cap 322 60 is provided for maintaining the entire assemblage in proper position. The plate 317 is formed with an opening 323 connected by a tube 324 with a suitable source of suction (not shown). The plate 320 may be integral with rod 306 and have an opening 325 communicating with bore 316. This plate additionally has a passage 326, one end of which may be aligned with opening 323, and the other end of which may be connected to a tube 327. The lower end of this tube is connected to opening 310, formed in head 307. Plate 321, as shown in Fig. 45, has an opening 321, which communicates through tube 328 with a source of air pressure (not shown). This plate 70 also has formed in its face a curved passage-

way 329, having its upper end in communication with opening 327 and its lower end communicating with an opening 330. Arms 331 extend from plate 317. An arm 332 extends from plate 321. These arms cooperate with an actuator 333, secured to a standard 334 mounted by the bracket or support 298. They also cooperate with actuators 335 and 336, respectively, disposed adjacent the opposite limits of movement of the carriage unit 297. Actuator 335 may be simply 10 in the form of a bracket mounted by a support 337 affixed with respect to the machine frame, while actuator 336 may be in the form of bar 338, which, as shown in Fig. 41, is rocked by a link 339, to which a spring 340 is connected, and 15 which mounts a follower 341 cooperating with a cam 342, which, as shown in Fig. 4, may be connected to the same shaft 167 which drives cam 166.

With plate 317 shifted to a position at which 20 opening or port 323 communicates with bore 326, tube 327 and port 310 are connected to the source of suction and if, by means of one of the rods 331, the plate 317 is shifted to a different position, such suction will be interrupted. If 25 plate 321, by means of actuator 332 is shifted so that port 327', through groove 329, connects with port 330, pressure will flow through bore 316 into cylinder 315 to lower the piston 313 and plate 308. Conversely, when the parts are in this position and the air pressure is cut off, the spring 314 will elevate the piston and consequently retract the plate 308 to a position at which it is housed within head 307. The operation of this mechanism will follow station No. 6 in the following cycle: Head 297 will be brought, by means of link 299, to a position at which it overlies the collar or tray 294. Upon the head 307 being depressed, it will frictionally engage the inner faces of the side flanges of the collar or tray. If this collar be in the form of a tray, the parts will be 30 additionally maintained against displacement, due to the fact that at this moment suction would act through tube 327. The head 307 will now rise and the carriage will be moved inwardly to 35 a point at which the head overlies unit 96. The head will now lower, the suction through tube 327 will be interrupted and pressure will flow from tube 328 through bore 316 to project plate 308 and press the same firmly towards the base of 40 the box unit. Consequently the collar or tray will likewise be firmly pressed into contact with the adhesive coating the inner faces of this box unit, and the parts will thus remain in contact while the head 307 withdraws to elevated position, it being understood that during at least the initial stages of such withdrawal the plate 308 45 remains in contact with the tray to prevent the latter from moving upwardly with the head. Thereupon the pressure to cylinder 315 is interrupted and the parts restored to their normal condition, the cycle being repeated indefinitely. The turntable now moves to station No. 7, at 50 which the intimacy of engagement of the tray or collar with the box base is assured.

Reference is had to Figs. 47 and 48 in which the mechanism at this station is illustrated in detail. As shown a cylinder 343 carries a piston rod 344 extending downwardly therefrom. This rod is normally retracted, as for example 55 by springs 345, and ports 346 and 347 are provided in the usual manner for allowing fluid under pressure to enter the cylinder while exhaust ports 348 are also provided. The rod 344 mounts a collar 349 to which screw-threaded 60

rods 350 are rockingly secured. A head 351 is slidably and adjustably connected to rod 344, relative movements being limited, as for example, by a slot and pin connection 352. A coiled compression spring 351' is interposed between the collar 349 and the upper part of the head 351, so as to yieldingly resist movement of these parts toward each other. Jaws 353 are pivotally secured to the head 351 and have their upper ends adjustably connected as at 354 to the screw-threaded rods or bolts 350. The lower end 355 of the head 351 is of an area proper for entrance into the tray or collar supported by the box unit, and it will thus be apparent, with the head in a position overlying the box unit at station No. 7, and the turntable in a position of rest, that by simply admitting air through port 346, the head 351 will be lowered until the outer end 355 thereof seats snugly within the collar or tray. Thereupon, due to the fact that the head may have limited upward movement with respect to the rod, and moreover, due to the fact that the upper ends of the clamping jaws 353 are connected to the collar 349, it will be obvious that the lower ends of these jaws will move inwardly with respect to the box members, the parts of which are in face to face contact and which are coated with adhesive, and force the same into such engagement with each other that there will be no danger of subsequent relative displacement thereof.

Referring to the valve structure by means of which the various cylinders are preferably controlled, as shown in Fig. 4, two valves are employed, being generally indicated by the numerals 356, and 357. The first valve controls the cylinder 228 at station No. 4, and cylinder 343 at station No. 7. The second valve controls the cylinder 250 of station No. 5 and cylinder 381 of station No. 6. Both valves are identical insofar as structure is concerned, it being observed that valve 356 is actuated by a rod 358 mounting a follower 359 for cooperation with a cam 360 secured to shaft 80, while valve 357 is actuated by means of a rod 361 secured respectively to the valve and a crank arm 362. This crank arm is connected to a second arm 363, which, by means of a rod 364 and a follower 365, cooperates with cam 366. The cam is mounted upon a shaft 367 which, by means of actuators 358, may have a two to one movement relative to shaft 76, it being of course noted that in each actuation of the cylinders controlled by valve 356, two actuations of the cylinders controlled by valve 357 will occur.

The structure of the valve may include, as shown in Figs. 12, 13, and 14, a fixed plate 369 formed with ports 370 and 371 connected respectively to the upper and lower ports of the cylinders in question. Adjacent the plate is a rotatable body 372, which, by means of a tube 373 is connected to a source of air pressure (not shown). This body is also formed with a groove 374 in that face which is adjacent plate 369, and it is this body which is rocked by the rods 358 or 361 (Fig. 4). With the body 372 in proper position it will connect the air pressure line 375 to one of the tubes 370 or 371. That cylinder tube which is not connected to the source of pressure will connect through the groove 374 and port 375 with a muffler 376' and consequently when one of the pistons is moving so that air will be exhausted at one side of the cylinder this air may be discharged with a minimum of interference or annoyance. The

members 376 beyond the body 372 may be of ordinary type and serve merely to retain the parts properly adjacent each other.

Now considering station No. 8, at which the completed unit is discharged, referring to Figs. 49, 50, and 51, rails 377 in the form of bars overlying the turntable 66 adjacent this station extend well beyond the same and over the deck 378. The rails may be supported as at 379 and slidably mounted thereon is a carriage 380 which is reciprocated by being connected to a rod 381. This rod, as illustrated in Fig. 50, may be connected to one arm of a bellcrank lever 382, the opposite arm of which is connected to a link 383. This link, as in Figs. 2 and 51, is attached to a bar 384 rockingly mounted as at 385, and disposed in spaced relationship to a similarly mounted bar 386. Associated one with each of these bars are followers 387 cooperating respectively with cams 388 and 389.

The connection between the rod 381 and the carriage is preferably provided by utilizing a rocker arm 390, pivotally secured to the carriage and to the rod, and link connected as at 391 to a crank 392 supported by such carriage. A contact plate 393 is secured to the crank and consequently when a thrust is exerted upon the rod 381 inwardly or to the right in Fig. 49, the carriage will move to the right along the rails 377 to a position at which it overlies the box unit. Under such inward movement of the carriage, it will be obvious that the contact plate or finger 393 will be maintained in the elevated condition shown in Figure 49. Accordingly, this part will not contact with any receptacle portion as the carriage moves in the manner described. If, thereupon, a pull to the left is exerted upon rod 381, the rocker arm 390 will be initially shifted to the left and the plate 393 lowered to the dotted line position indicated in Figure 49, and with the plate in such position the carriage will now move outward. Thereupon the receptacle unit will be engaged by the plate 393 and moved from a position on the turntable to a position upon the deck 378. Preferably, the latter has guiding strips 394 to define a path of travel for the receptacle. It is, of course, obvious that any desired form of delivery mechanism might be associated with deck 378 for the purpose of automatically shifting the completed receptacles there-along. Also, as shown in Fig. 50, the contact plate 393 may be in the form of two arms engaging one within each of the receptacle portions so that no undue strain will be thrown upon the hinge 188.

Finally, it will be appreciated that it might be desirable to employ mechanisms which will assure that the turntable comes to a stop, not alone at positions corresponding to the stations described, but also at positions where it is minutely correlated to the mechanism at such stations. If such provision is desired, there may be connected with the turntable 66, as shown in Figs. 1, 4 and 5 a series of pins 395 which correspond in number to the number of stations provided. Engageable with these pins is a latch member 396 which may be swung to position by means of a spring-pressed link 397 operated by a lever 398, which mounts a follower 399 cooperating with a cam 400. This cam is obviously timed so that as the turntable is rotated to a position adjacent which the several areas are properly disposed with reference to the mechanisms which are to cooperate therewith, the latch member 396 is swung upwardly, cooperating with one of the pins 395, to

assure proper registration and to lock the parts against further movement. Cam 400, being secured to the shaft 80, it will be obvious that this cam will be timed to release the latch before the turntable shifting mechanism again operates.

Reviewing briefly the operation of the entire machine, the motor 69 is set in operation and the clutch parts 71—72 are engaged. Prior to that time a supply of receptacle units is disposed upon the conveyor 88 and the glue pot is filled. The magazine containing the hinge strips or members 188 is also filled and the conveyor 282 receives in any suitable manner a supply of collars or trays. The stop 104 (Figs. 20 to 24) acts to prevent the receptacle portions being fed beyond a predetermined point and these portions or units are then transferred to the turntable 66. If any jamming of the parts occurs, contacts 120 will engage to thus automatically throw the clutch by means of the control 94 (Fig. 4). During such transfer the presser foot or strip 139 is in elevated condition incident to the depression of the rail 142. Likewise, the framing member 126 (Figs. 3 and 27) is swung to open condition due to the cooperation of the follower 131 with the cam disk or ring 132. Thereupon, the turntable 66 shifts to the second station (Figs. 25, 26, and 27) where the receptacle portions are brought into horizontal and vertical alignment by the presser foot 165 and contact bars 152. At the next station (Figs. 28 and 29), hinge strips or members 188 are coated with glue and brought to a position overlying those side edges of the receptacle portions which are adjacent to each other and are moved into contact with such edges by the head 180. At station No. 4 (Figs. 33 to 35) the jaws 241 serve to press the strip surfaces into contact with the inner surfaces of the receptacle flanges, and the plate 245 presses the strip or hinge member into contact with the upper adjacent edges of the receptacle flanges. Thereupon, at station No. 5 (Figs. 36 to 38) the surface 271 of head 270 coats the base of that receptacle portion 96 which is to be the base of the box, and the inner side faces of such unit are coated by the contact members 267. The tray or collar member 294 is placed in position within the adhesively coated box part or unit 96 at station No. 6, as particularly shown in Figs. 39 and 40. At the next station, No. 7 (Figs. 47 and 48), the tray or collar member is pressed intimately into contact with the base portion receptacle and at station No. 8 (Figs. 49 and 50) the completed receptacle is discharged from the machine.

Obviously, numerous changes in construction and re-arrangements of the parts might be resorted to without departing from the spirit of the invention as defined by the claims.

Having described my invention, what I claim as new and desire to secure by Letters Patent is:

1. A machine of the class described, including means for receiving receptacle portions, means for applying a hinge strip to the inner faces of such receptacle portions and means for applying a flanged member to one of said receptacle portions to lock said strip against displacement.

2. A machine of the class described, including means for receiving receptacle portions, means for applying a hinge strip to the inner faces of such receptacle portions, means for coating one of such receptacle portions and means for applying to said coated portion, a flanged member lying beyond and in contact with such hinge strip.

3. A machine of the class described, including means for receiving receptacle portions, means

for applying a hinge strip to the inner faces of such receptacle portions, means for coating the applied hinge strip and means for delivering a retaining member to one of said receptacle portions and pressing the same into contact with said coated strip.

4. A machine of the class described, including means to place receptacle portions adjacent to each other, means to receive a hinge portion, means for adhesively coating one of such portions and means for bringing the surfaces of such receptacle portions into intimate contact with said hinge portions and with each other.

5. A machine of the class described, including means to receive receptacle portions, means to receive a hinge portion, means for adhesively coating one of such portions, means for delivering said hinge portion to an overlying position with respect to said receptacle portions and additional means for pressing such receptacle portions and said hinge portion into intimate contact with each other.

6. A machine of the class described, including means to receive a receptacle portion, means to bring a hinge strip into contact therewith, means to force said hinge strip into permanent engagement with said portion, means to thereafter receive a flanged portion, means for coating one of said portions and means for moving said portions into contact.

7. A machine of the class described, including means to receive a receptacle portion, means to bring a hinge strip into contact therewith, means to force said hinge strip into permanent engagement with said portion, means to thereafter receive a flanged portion, means for coating one of said portions and means for thereupon forcing such portions into intimate engagement.

8. A machine of the class described, including receptacle framing means, shiftable means forming a part of said last named means, means acting upon a receptacle being received by said framing means to move said shiftable means and means for thereupon applying additional parts to the receptacle portion.

9. A machine of the class described, including receptacle receiving means including a base, means for pressing a receptacle portion towards said base, means for delivering a receptacle portion to said base, means for rendering said pressing means inoperative during such delivery and means for subsequently applying parts to said receptacle portion.

10. A machine of the class described, including receptacle receiving means, means for delivering a plurality of receptacle portions thereto and means for subsequently registering said portions, one with respect to the other.

11. A machine of the class described, including receiving means, means for delivering a plurality of receptacle portions to said receiving means, means for aligning said portions with respect to each other, means for thereupon retaining said portions immovable with respect to said receiving means, means for delivering a strip to said receptacle portions, means for applying said strip to bridge and overlie such receptacle portions, means for coating the surfaces of one of said receptacle portions, means for delivering a flanged member to such coated portions and means for forcing said flanged member into intimate engagement with said portions.

12. A machine of the class described, including receiving means, means for delivering a plurality of receptacle portions to said receiving

- means, means for aligning said portions with respect to each other, means for thereupon retaining said portions immovable with respect to said receiving means, means for delivering a strip to said receptacle portions, means for applying said strip to bridge and overlie such receptacle portions, means for coating the surfaces of one of said receptacle portions, means for delivering a flanged member to such coated portions, means for forcing said flanged member into intimate engagement with said portions and means for thereupon delivering the receptacle from the machine.
13. The method of forming a receptacle which comprises taking two pre-formed receptacle portions and joining them to each other by means of a flexible hinge member and thereafter locking said hinge member in position by means of a collar portion inserted in one of said receptacle portions.
14. The method of forming a receptacle which comprises taking two receptacle portions provided with side wall members and securing said portions together by means of a flexible hinge which is positioned over adjacent side wall members in said receptacle portions and thereafter inserting a collar portion into one of said receptacle portions whereby said hinge member is locked in position.
15. In a machine of the character described, in combination, means for applying a hinge strip to the face to face adjacent wall sections of receptacle portions, and means for pressing remote portions of said strip into adhering contact with the remote opposite surfaces of said adjacent face to face wall sections.
16. In a machine of the character described, in combination, means for applying a hinge strip to the face to face adjacent wall sections of receptacle portions, means for pressing remote portions of said strip into adhering contact with the opposite surfaces of said adjacent wall sections, and means for applying a binding element in binding position against one of said applied hinge strip portions.
17. In a machine of the character described, means for applying a hinge strip to the upstanding adjacent wall sections of receptacle portions, each having wall sections encompassing a head portion and upstanding therefrom, means for pressing remote portions of said hinge strip into adhering contact with the opposite surfaces of said adjacent wall sections, and means for applying and securing in position a collar member within said encompassing wall sections of one receptacle portion and in binding position against the applied hinge strip.
18. In a machine of the character described, in combination, means for positioning side by side receptacle portions having upstanding wall sections, with the upstanding wall sections of the said portions adjacent to each other, means for applying a hinge strip to said adjacent wall sections, and means for pressing remote portions of said strip into adhering contact with the opposite surfaces of said adjacent wall sections.
19. In a machine of the character described, in combination, means for positioning side by side receptacle portions having upstanding wall sections, with the upstanding wall sections of the said portions adjacent to each other, means for applying a hinge strip to said adjacent wall sections, means for pressing remote portions of said strip into adhering contact with the opposite surfaces of said adjacent wall sections, and means
- for applying a binding element in binding position against one of said applied hinge strip portions.
20. In a machine of the character described, in combination, means for positioning, side by side, receptacle portions having upstanding wall sections, with the upstanding wall sections of the said portions adjacent to each other, means for rendering a hinge strip adhesive, and means for applying said hinge strip adhesively to the upper edges of said adjacent wall sections, and for pressing remote portions of said strip into adhering contact with the opposite surfaces of said adjacent wall sections.
21. In a machine of the character described, in combination, means for positioning, side by side, receptacle portions having upstanding wall sections, with the upstanding wall sections of the said portions adjacent to each other, means for rendering a hinge strip adhesive, means for applying said hinge strip adhesively to the upper edges of said adjacent wall sections, and for pressing remote portions of said strip into adhering contact with the opposite surfaces of said adjacent wall sections, means for applying a binding element in binding position with reference to the applied hinge strip, and means for applying adhesive to hold said binding element in binding position.
22. In a machine of the character described, in combination, receptacle receiving means, means for transferring a plurality of separate unattached receptacle parts to said receiving means, and relatively movable members for relatively positioning said receptacle parts both vertically and horizontally.
23. In a machine of the character described, receptacle receiving means, means for transferring a plurality of separate unattached receptacle parts to said receiving means, means for relatively positioning said receptacle parts both vertically and horizontally, and means for attaching said receptacle parts together after they have been aligned by said positioning means.
24. In a machine of the character described, in combination, receptacle receiving means, means for transferring a plurality of separate unattached receptacle parts to said receiving means, means for relatively positioning said receptacle parts both vertically and horizontally, and means for applying a hinge strip to adjacent parts of said receptacle parts after they have been aligned by said positioning means so as to hingedly connect them.
25. In a machine of the character described, in combination, receptacle receiving means, means for transferring a plurality of receptacle parts to said receiving means, means for relatively positioning said receptacle parts both vertically and horizontally, means for applying a hinge strip to adjacent parts of said receptacle parts so as to hingedly connect them, and means for applying a collar member to one of said receptacle parts in binding relation with said applied hinge strip.
26. In a machine of the character described, in combination, receptacle receiving means, means for transferring a plurality of receptacle parts to said receiving means, framing elements included in said receiving means for positioning said receptacle parts, and means for moving certain of said framing elements for aligning and positioning said receptacle parts.
27. In a machine of the character described, in combination, receptacle receiving means, means

for transferring a plurality of receptacle parts to said receiving means, framing elements included in said receiving means for positioning said receptacle parts, means for moving certain of said framing elements for aligning and positioning said receptacle parts, and pressure means engaging said receptacle parts from above to align and position them in a different direction.

28. In a machine of the character described, in combination, receptacle receiving means, means for transferring a plurality of separate independent receptacle parts to said receiving means, and movable elements mounted on said receiving means and being engageable with different angularly disposed surfaces of a plurality of said receptacle parts upon said receiving means, so as to align and position them in different angularly disposed planes.

29. In a machine of the character described, in combination, receptacle receiving means, and movable elements mounted on said receiving means and being engageable with different angularly disposed surfaces of a plurality of receptacle parts upon said receiving means, so as to align and position them in different angularly disposed planes.

30. In a machine of the character described, in combination, receptacle receiving means, and movable elements engageable with different angularly disposed surfaces of a plurality of receptacle parts upon said receiving means, so as to align and position them in different angularly disposed planes, a plurality of said movable elements being positioned to engage different sides of said receptacle parts to adjust them in different directions in the same plane.

31. In a machine of the character described, in combination, receptacle receiving means, and movable elements engageable with different angularly disposed surfaces of a plurality of receptacle parts upon said receiving means, so as to align and position them in different angularly disposed planes, one of said movable elements being positioned simultaneously to engage adjacent wall portions of said receptacle parts to bring them into alignment with each other.

32. In a machine of the character described, in combination, receptacle receiving means, and movable elements engageable with different angularly disposed surfaces of a plurality of said receptacle parts upon said receiving means, so as to align and position them in different angularly disposed planes, a plurality of said movable elements being positioned to engage different sides of said receptacle parts to adjust them in different directions in the same plane, one of said movable elements being positioned simultaneously to engage adjacent wall portions of said receptacle parts to bring them into alignment with each other.

33. In a machine of the character described, in combination, receiving means for receptacle parts, means for transferring receptacle parts to said receiving means, means for hinging together two receptacle parts on said receiving means transferred thereto by said transferring means, means for driving the machine, and automatic means controlled by said transferring means for rendering said driving means inoperative to drive the machine upon jamming of the receptacle parts being transferred.

34. In a machine of the character described, in combination, receiving means for receptacle parts, a transfer carriage, a transfer arm pivoted on said carriage and movable therewith for trans-

ferring receptacle parts to said receiving means, means for driving the machine, and automatic means controlled by pivotal movement of said transfer arm upon jamming of the receptacle parts being transferred, to render said driving means inoperative.

35. In a machine of the character described, in combination, receiving means for receptacle parts, means for transferring receptacle parts to said receiving means, means for driving the machine, automatic means controlled by said transferring means for rendering said driving means inoperative to drive the machine upon jamming of the receptacle parts being transferred, a carrier to position receptacle parts in position for transfer by said transferring means, and a checking member controlled by said transferring means to check movement of the receptacle parts by said carrier during a transfer operation by said transferring means.

36. In a machine of the character described, in combination, receiving means for receptacle parts, a transfer carriage, a transfer member pivoted to said carriage, a carrier to place receptacle parts in position for transfer thereof by said transfer member, and means for operating said carriage to simultaneously transfer a plurality of adjacent receptacle parts from said carrier to said receiving means.

37. In a machine of the character described, in combination, receiving means for receptacle parts, a transfer carriage, a transfer member pivoted to said carriage, a carrier to place receptacle parts in position for transfer thereof by said transfer member, means for operating said carriage to simultaneously transfer a plurality of adjacent receptacle parts from said carrier to said receiving means, and a checking member carried by said carriage and movable therewith into position to check movement into transfer position of receptacle parts during a transfer operation of said transfer carriage.

38. In a machine of the character described, in combination, a magazine for carrying a stack of hinge strips, a plurality of strip guiding fingers with pneumatic nozzles for releasing strips from the stack, a pneumatic head for pneumatically engaging a strip to remove it from the stack, a second pneumatic head to which the strip is transferred by said first head, a third pneumatic head, means for pneumatically transferring the strip from said second head to said third head and holding it by the latter, and means for pneumatically transferring the strip from the third head to apply it to a box part.

39. In a machine of the character described, a magazine for carrying a stack of hinge strips, a plurality of strip guiding fingers with pneumatic nozzles for releasing strips from the stack, a pneumatic head for pneumatically engaging a strip to remove it from the stack, a second pneumatic head to which the strip is transferred by said first head, a third pneumatic head, means for pneumatically transferring the strip from said second head to said third head and holding it by the latter, means for pneumatically transferring the strip from the third head to apply it to a box part, and an adhesive applicator for applying adhesive to the hinge strip being carried by said third head.

40. In a machine of the character described, in combination, means for applying a hinge strip to the inner surfaces of adjacent side walls of receptacle elements, means for pressing said strip to the edges of said adjacent parts, and oppositely

disposed presser jaws for pressing said strips against the opposite inner faces of said adjacent side walls.

41. In a machine of the character described, in combination, means for applying a hinge strip to adjacent parts of receptacle elements, means for pressing said strip to the edges of said adjacent parts, oppositely disposed presser jaws for pressing said strip against the opposite faces of said adjacent parts, an adhesive applicator for applying adhesive to one of the receptacle elements and including independently movable applying elements for applying adhesive to different surfaces of receptacle element, and means for applying a collar element and pressing it into contact with said adhesively treated surfaces.

42. In a machine of the character described, in combination, an adhesive applying member for applying adhesive to a box part, a second adhesive applying member, means for placing adhesive on both of said applying members, and means for operating said applying members simultaneously for applying adhesive carried thereby to different angularly disposed surfaces of said box part.

43. In a machine of the character described, in combination, an adhesive applying member for applying adhesive to a box part, a second adhesive applying member mounted for pivotal movement with reference to said first mentioned applying member, and means for operating said applying members simultaneously for applying adhesive to different angularly disposed surfaces of said box part.

44. In a machine of the character described, in combination, an adhesive applying member for applying adhesive to a box part, a second adhesive applying member, an operating head supporting said applying members, and means for controlling said head for simultaneously moving said applying members into contact with angularly disposed surfaces of said box part.

45. In a machine of the character described, in combination, an adhesive applying member for applying adhesive to a box part, a second adhesive applying member, an operating head supporting said applying members, said second applying member being mounted for swinging movement, means for mounting said first applying member for relative movement with reference to said head, and link connection between said head and said second applying member to effect swinging movement of the latter.

46. In a machine of the character described, in combination, an adhesive applying member for applying adhesive to a box part, a second adhesive applying member, an operating head supporting said applying members, means for controlling said head for simultaneously moving said applying members into contact with angularly disposed surfaces of said box part, and an adhesive applicator for applying adhesive to both of said adhesive applying members.

47. In a machine of the character described, in combination, a head for associating box parts one with another and adapted to receive and retain a box part, a carriage for moving said head and carrying a pneumatic cylinder operatively connected to the head for reciprocation thereof, an ejector for the box part, pneumatic means for operating said ejector, and automatic means controlled by movement of said head for controlling pneumatic power supply to said ejector operating means.

48. In a machine of the character described, in combination, a head for associating box parts

one with another and adapted to receive and retain a box part, a carriage for moving said head and carrying a pneumatic cylinder operatively connected to the head for reciprocation thereof, an ejector for the box part, pneumatic means for operating said ejector, and automatic means controlled by movement of said head for controlling pneumatic power supply to said ejector operating means, said automatic means including a valve connected for reciprocation with 10 said head.

49. In a machine of the character described, in combination, a head for associating box parts one with another and adapted to receive and retain a box part, a carriage for moving said head and carrying a pneumatic cylinder operatively connected to the head for reciprocation thereof, to apply one box part to another, means for applying a mandrel to the box parts thus associated, pivotally mounted pressure jaws associated with said mandrel, and means for operating said jaws to firmly press the box parts together.

50. In a machine of the character described, in combination, a turntable, means for rotating 25 said turntable intermittently to carry receptacle elements carried thereto into different successive operative stations, mechanisms for performing different operations upon the receptacle elements at the different stations, a plurality of retaining 30 pins mounted on the edge of said turntable and being peripherally spaced thereon, a pivotally mounted holding and correlating lever positioned for engagement with said retaining pins, and means for operating said holding lever to engage 35 the respective retaining pins to hold said turntable in correlated position for operations at the different stations.

51. In a machine of the character described, in combination, a turntable, means for rotating said 40 turntable intermittently to carry receptacle elements carried thereby into different successive operative stations, mechanisms for successively at different stations positioning and aligning the receptacles with reference to each other and adhesively applying a hinge strip to attach the receptacle elements together, retaining elements mounted upon said turntable and adjacent thereto for locking said turntable in each of its said operative stages, and including a movably mounted member, and means for moving said movably mounted member to and from locking position in synchronism with movement of said turntable.

52. A method for forming a receptacle including placing side by side two receptacle parts 55 with side wall members thereof adjacent to and in parallel relation with each other, and then applying a flexible hinge strip over the edges of said adjacent side wall members when the latter are in parallel relation and pressing it into 60 adhesive contact with the opposite faces of the side wall members, and adhesively attaching a locking member in position to contact with said applied hinge strip to hold the latter in position.

53. A method for forming a receptacle including placing side by side two receptacle parts with side wall members thereof adjacent to and in side by side parallel relation with each other, then applying a flexible hinge strip over the edges of said adjacent side wall members when 70 the latter are in parallel relation and applying pressure in opposite directions to the opposite parts of the applied hinge strip to press it into adhesive contact with the opposite inner faces of the side wall members, and then locking said 75

hinge strip in position by a permanent pressure device.

54. A method for forming a receptacle including placing side by side two receptacle parts with side wall members thereof adjacent to each other, then applying a flexible hinge strip over the edges of said adjacent side wall members and pressing it into adhesive contact with the opposite faces of the side wall members, and then inserting a permanent pressure member into pressure relation with said hinge strip so as to exert permanent pressure against said strip to support the latter in position.

55. A method of forming a receptacle including placing side by side two receptacle parts with side wall members thereof having their outer side surfaces together in parallel relation, and then adhesively applying a flexible hinge strip to both of said side wall members against the inner surfaces thereof and applying pressure in opposite directions against said hinge strip and side wall members.

56. A method of forming a receptacle including placing side by side two receptacle parts with side wall members thereof having their outer side surfaces together, then bending a flexible hinge strip over the edges of said side wall members and pressing remote parts of the hinge strip into adhesive contact with the inner side surfaces of said side wall members, and thereafter inserting a collar portion into one of said receptacle parts in locking relation with said hinge strip.

57. In a machine of the character described, in combination, receptacle receiving means, movable elements movable into engagement with different angularly disposed surfaces of a plurality of unhinged physically separate receptacle parts upon said receiving means so as to align and position them in different angularly disposed planes, and means acting after the aligning action of said movable elements for moving a separate hinge element into position and applying it for hinging said receptacle parts to-

gether when in the position in which they have been aligned by said movable elements.

58. In a machine of the character described, in combination, receiving means, means for aligning unhinged physically separate receptacle parts with reference to each other on said receiving means, and means acting after the aligning action of said aligning means for moving a separate hinge element into position and applying it for hinging said parts together when in the position in which they have been aligned by said aligning means.

59. In a machine of the character described, in combination, rotary receiving means, a plurality of aligning devices mounted upon said rotary receiving means, means for successively operating said aligning devices for aligning unhinged receptacle parts with reference to each other on said receiving means, and means for successively hinging said parts together as aligned by said aligning means.

60. In a machine of the character described, in combination, receiving means, means for aligning receptacle parts with reference to each other on said receiving means, and means acting after the aligning action of said aligning means for moving a separate hinge element into hinging position and adhesively applying it to the inner surfaces of receptacle parts when the latter are in the position in which they have been aligned by said aligning means.

61. In a machine of the character described, in combination, receiving means, means for aligning unhinged receptacle parts with reference to each other on said receiving means, and means acting after the aligning action of said aligning means for moving a separate hinge strip into position to hinge said receptacle parts together and to press said strip into adhesive contact with said receptacle parts when the latter are in the position in which they have been aligned by said aligning means.

HAROLD C. COPPINS.
